A. L. TRAVER

GUIDE AND ADJUSTER FOR LOOPER NEEDLES

Original Filed Feb. 17, 1920

Patented Dec. 4, 1923.

1,476,659

UNITED STATES PATENT OFFICE.

ADELBERT L. TRAVER, OF PHILMONT, NEW YORK.

GUIDE AND ADJUSTER FOR LOOPER NEEDLES.

Application filed February 17, 1920, Serial No. 359,388. Renewed June 8, 1923.

To all whom it may concern:

Be it known that I, ADELBERT L. TRAVER, a citizen of the United States, and resident of Philmont, in the county of Columbia and State of New York, have invented a new and Improved Guide and Adjuster for Looper Needles, of which the following is a full, clear, and exact description.

This invention relates to the sewing machine art, and especially to looper machines employed to join together knit fabric apparel. More particularly the invention relates to the needle mechanism of looper machines, and discloses a guide and adjuster for holding the needles of a machine in proper sewing relation one with the other.

The primary object of the invention is to produce new and improved needle adjusting means, and guide means for use in connection with multiple needle looping machines; and more in particular for use in connection with my two thread overstitch looper disclosed in an application for patent filed August 28th, 1919, and identified under the Serial No. of 320,491.

A further object is to produce a guide adjuster for loopers which may be installed on looper machines in general use and function to hold two or more needles in proper relative sewing position in order that the work done by the looper machines will be generally improved.

The class of looper machines described in the above identified copending application for patent, embodies two or more sewing needles or looper needles, each of which are independently driven in synchronized motion one with the other. It is necessary that the needles be very accurate in movement, and if they get out of adjustment due to slight wear in the parts, the needles will no longer follow the original course but deviate therefrom enough to thwart or prevent the proper sewing relation. When this condition exists, the needles, or the looper and the needle, as they are known, will not follow each other by moving into adjacent relation to perform the looping of the thread and drawing of the stitch; thus the machine occasionally drops a stitch and fails to properly function.

It is obvious that a need is felt for some simplified means for correcting the above described slight ineffectiveness of looper machines; and it is fitting therefore that the primary object of my invention is to

fulfil this need by disclosing and producing a guide adjuster for loopers which will hold the stitch needle in positive position while the looper moves relatively and adjacent the stitch needle to execute the looping and drawing of the stitch.

With the above principal and other objects in view, the invention has relation to the combination and arrangement of looper machine parts, as defined in the appended claims; and one practical example of which is presented in the following paper and portrayed in the accompanying drawings, wherein:

Figure 1 discloses a side elevation of my looper machine as embodied in the application for patent Serial No. 320,491, and parts of which looper machine are broken away to disclose the most important features. This looper machine shows the attachment features embodying a guide adjuster for loopers constructed in accordance with this invention.

Figure 2 shows a plan view of part of Figure 1, or more particularly discloses a sectional view taken on the line 2—2.

Figure 3 discloses a fragmentary plan view illustrating the manner of attaching the guide to the machine and showing the relation of said guide with the stitch needle.

Figure 4 illustrates a rear elevation of Figure 3 as developed on the line 4—4.

Figure 5 discloses a partial sectional view as taken on the line 5—5 of Figure 1 to show the looper mounted in an adjuster, said adjuster parts being in section.

Figure 6 illustrates a sectional view taken on the line 6—6 of Figure 2 to show a needle guide in action, and also shows a means for adjustably holding the looper in the machine.

Figure 7 illustrates a sectional view taken on the line 7—7 of Figure 6 to disclose the aligned relation between the stitch needle and the looper.

Figure 8 illustrates a side elevation and edge view projection of a spliced extensible link employed to work the looper, said link having an extension adjustment to enable the operator to maintain the looper in correct and accurate working relation with a stitch needle.

An attachment known as a guide adjuster for the needles of looper machines constructed in accordance with the plans of the invention employs a guide or receptacle for

holding the stitch needle against vibration or lateral motion when it completes the end of its stroke. The looper is mounted on the usual oscillating shaft, and the shaft is carried in an adjustable device so arranged as to enable the operator or looper-machine mechanic to change the plane in which the looper swings or gyrates in order to cause the looper to swing up in closely adjusted relation with the solidly held stitch needle for executing the looping and drawing of the stitch during the operation of joining the two knitted fabrics together.

In presenting a more detail description of the invention, there is shown in the drawings any appropriate form of looper machine for joining knit fabrics, but more particularly showing my looper as embodied in the above heretofore identified application for patent; and mounted upon this looper machine there is shown the guide adjuster for the loopers. Referring now more in particular to the drawings, there is shown a base or bolting plate 14 upon which is mounted a frame arm 15. The frame arm holds a vertical shaft or stem 16 on the lower end of which is fixed a circular plate frame carrying a rotated drum or cylinder 17 having a gear 18 fixed thereto and meshing with a drive pinion 19 which is fixed to a drive shaft 20.

As is known to those conversant in the art, and as disclosed in my former and above identified application for patent, there is provided a step-by-step driving means for rotating the cylinder 17. The cylinder 17 carries the fringe of impaling points 22 which radiate from the periphery of the cylinder and are provided for the purpose of holding the two knit fabrics which are to be joined together. The points 22 of the impaling fringe are slotted or grooved by cutting channels 23 in the points; and as understood by those conversant in the art, the stitch needle as later described, oscillates back and forth longitudinally in approximately parallel relation to the points 22 and moves into close co-operating position with the points by passing along or through the channels 23 to go through the loops of the two knit fabrics hung on the impaling fringe. A guard ring 25 is made concentric with the cylinder 17 and spaced slightly therefrom. This guard ring is placed closely adjacent to and underneath the impaling fringe 22 for the purpose of holding the knit fabrics in proper position on the points while the needle is executing the stitches.

A needle arm 27 is pivotally mounted on a bearing 28 fixed to the frame 15. This needle arm is subjected to appropriate oscillating or gyrating motion and carries on the lower end thereof the stitch needle 29. The stitch needle is carried approximately radially with the cylinder and in parallel

relation to the impaling fringe points; and this needle is subjected to high speed oscillating motion imparted thereto by suitable driving means as disclosed in my former application for patent. A looper arm 30 is pivotally mounted on a bearing 31 carried on the frame of the machine, and is likewise actuated by suitable driving mechanism to cause the outer and lower end thereof to undergo an up and down oscillating motion. The outer end of this looper arm 30 is shown in further details in the Figures 5 and 6.

The above and foregoing description presents a general résumé of the parts of a looper machine which is necessary to be understood in order that a clear conception be obtained of just how the combination guide adjuster for the needles may be used in connection therewith. The following description covers especially the parts and details of my invention, it being understood that variations and modifications in design, construction and operation may be made without departing from the scope of the invention as defined in the appended claims.

The looper arm is notched out on the end to provide an ear 32, and a clamp bracket 33 is pivoted to the ear by a pin or screw 34. By tightening down on the screw 34 the clamp bracket 33 is held in fixed relation with the looper arm 30. The clamp bracket may be adjusted in alignment with the arm 30 or it may be set at an angle to the arm. The clamp bracket 33 is split and provided with a bore through which is inserted a journal sleeve 35. The journal sleeve 35 is clamped in position when the screw 34 is tightened down on the clamp bracket. An oscillating shaft 36 is confined in the bearing sleeve 35 and has fixed on one end thereof a collar 37, and on the other end thereof a rocker arm 38. The rocker arm is equipped with a ball joint on which an adjustable link 39 works to move the rocker arm 38 and oscillate the shaft 36. The collar 37 carries the looper 40 which is thrust into a bore made in the collar and shaft, and anchored in position by a clamp screw.

The parts just described constitute an adjuster mechanism for varying the working plane of the looper 40. It is seen how the screw 34 may be loosened and the clamp bracket 33 adjusted to a slight angle to the looper arm 30 by setting it over to either one side or the other, which would correspondingly swing the axis of the oscillating shaft 36 from its original position and act to change the position of the point of the looper 40. This adjuster means as described is used for varying the working position of the looper 40 for gaining a more efficacious performance of the looping functions of said looper.

The aforesaid adjustable link 39 is spe- 130

cially constructed to permit an adjustment of the looper 40, and the construction comprises a link or arm made in two parts and spliced to make the link extensible and adjustable in length. The curved arm 39 is provided with a slotted opening in the lower end thereof into which clamp screws are inserted. The link part 39^a is provided with tapped holes for the reception of the clamp 5 screws in order to positively anchor these two link parts together in fixed position. The spliced and adjustable link 39 has been separately illustrated in Figure 8 to thoroughly disclose its design and construction. 10 A comprehension of the structure of this link 39 will enable the understanding of its operation in connection with the machine for the purpose of effecting a certain adjustment in the swing or gyrations of the 15 looper 40. If this spliced link is lengthened out by loosening the clamp screws and sliding the spliced parts further apart, the rocker arm 38 is correspondingly depressed, which throws the upper portion of the 20 looper point 40 slightly further away from the impaling fringe 22; and, conversely, if the link 39 is shortened by sliding the spliced parts closer together, the upper portion of the looper 40 is brought into 25 closer relation with the impaling fringe. The adjustment of the looper 40 in Figure 30 6 is so made that it works quite close to the impaling fringe as well as in close proximity to the stitch needle 29. A very slight change in the length of the link or arm 39 35 is sufficient to correct the adjustment of the working point of the looper 40. This particular novel arrangement conceived and disclosed for rendering possible the adjustment 40 of the looper 40 in relation to the impaling fringe 22 is a highly important and improved feature as regards the sewing machine art, and, more particularly, looper machines for joining knitted fabrics together, since the operator is able to make 45 the looper 40 gyrate in close proximity to the impaling fringe without danger of hitting the pins 22 thereof, to the end that the working point of the looper 40 will always 50 accurately slip through the thread carried by the stitch needle 29 and thereby positively execute the desired loop and draw the thread to make a well-formed stitch. 55 It is seen, therefore, that this invention provides two independent adjusting means for the looper 40, one means constituting the extensible link 39, as portrayed in Figure 8; and the other means constituting the swiveled adjuster clamp bracket 33, as portrayed in the detail Figures 5, 6 and 7. The 60 first adjustment mentioned makes it possible for the looper needle 40 to be so accurately positioned in respect to the impaling fringe that it may be made to work very closely thereto; and the second adjustment 65

mentioned makes it possible to accurately position the looper 40 in respect to the stitch needle 29 so that the looper and the needle may be made to work in contiguous relation, that is to say, the needle 29 and looper 70 40 may be so finely adjusted by virtue of the swiveled clamp bracket that the looper 40 will work at high speed in approximately contacting relation with the stitch needle. It is to be noted that the extensible link 39, 75 makes it possible to adjust the looper 40 radially with the cylinder 17 which moves the upper point of the looper along the axis of the adjacent pin of the impaling fringe. 80 The needle 29 is provided with a guide or holder means to center it in fixed and positive relation after it has reached its advanced position of operation, and this accomplishment is obtained by employing a 85 guide, a description of which follows. A bracket 42 is fixed to the frame of the machine, and in the present instance is fixed to the guard 25. The bracket 42 is spaced somewhat from the guard and from the impaling fringe in order to clear the knitted 90 garment parts to be joined together, and in order to give clearance for the operation of the needles. The end of this bracket is split to form a pair of clamp arms 43, and a clamp screw 44 is screwed into the arms to 95 effect a clamped relation therebetween. A tubular guide 45 with a flared end 46 is held in the clamp arms 43 and anchored in fixed relation therewith by tightening up the screw 44. The member 45 is made in the 100 form of a tube flared at one end, or a holder or a socket, for the reception of the end of the stitch needle 29. This guide should be constructed of hardened steel, or other suitable material, in order that the flared opening 46 may divert the point of the stitch needle to the central portion of the tube, where said needle will come to a standstill with the point held fixed in the socket of the holder or tube 45, as shown in the 105 sectional plan view, Figure 3. The needle 29 oscillates back and forth in parallel relation to the impaling fringe 22; and upon each successive operation the needle 29 enters the tubular opening of the guide 45. The adjustment of the bracket 42 and guide receptacle 45 is such that the needle 29 freely enters the tube with the point of the needle centered in the opening of said guide to prevent it from vibrating or undergoing lateral 110 or up-and-down motion during the time that the looper needle is moving upwardly to effect a stitch. 115 The description in the foregoing paragraph relates directly to the guide for the 120 stitch needle of the looper machine, and it is seen how this guide will act to hold the outer free end of the stitch needle 29 in firm and immovable relation while other parts of the machine, and particularly the looper 125

of the machine, are carrying out their respective cycles of operation. Another function of the needle-retaining guide 45 is to hold the needle 29 in approximately parallel relation with the pins 22 of the impaling fringe so that the stitch needle 29 will be held in very close relation with the point 22 which holds the two loops of the knitted fabric parts to be joined together.

5 It is possible to make a separate application of the needle adjuster and needle guide to a machine. However, by employing only one of these devices, it is seen how the other needle could not be adjusted or held, as the 10 case might be, in proper moving relation with the companion needle. By employing the looper-adjuster mechanism in combination with the stitch-needle retaining guide, it is possible to so adjust the entire stitching mechanism of a looper machine to such a fine degree of mechanical effectiveness that it will not drop a single stitch, that is to say, the stitching mechanism will not fail to pass through each and every individual 15 loop of the knitted fabric, thereby doing better work than is possible with machines of present-day manufacture where stitching parts get out of adjustment due to wear which alters the path of travel of the points 20 of the needles.

25

In presenting a more detailed description of the movement of the needle 29 and looper 40, particular attention may be directed to Figures 6 and 7. The stitch needle 29 oscillates back and forth, and at the end of each stroke is centered and held by the guide 45. The looper 40 gyrates at an angle up and down and partly transversely of the stitch needle. The looper 40 must necessarily move 30 in very close relation to the needle 29 in order to pick up the thread carried by the needle 29 and effect the looping thereof by drawing the thread upwardly to execute a complete stitch. When the looper 40 does 35 not move in close relation to the needle 29, the thread carried by the needle 29 is missed by the looper 40 thereby dropping that stitch. When this occurs, it means that too much space is left between the looper 40 and 40 needle 29. This misadjustment is corrected by loosening the clamp screw 34 and readjusting the clamp bracket 33 so that the looper 40 is again brought into very close and approximately contiguous relation with 45 the needle 29. The ability to adjust the looper 40 and the ability to hold the needle 29 in immovable position are the controlling causes and means employed to get the best performance from a multiple-needle 50 looper machine for joining knitted fabrics.

Having thus described my invention, what I desire to secure by Letters Patent is:

1. A looper adjuster for looper machines, where the looper is provided with an oscillating arm, comprising a clamp bracket 55

pivoted on the oscillating arm, a bearing tube anchored in the clamp bracket, an oscillating shaft journalled in the bearing tube, a rocker arm fixed to the oscillating shaft, a ball joint made on the rocker arm, a link 70 confined on the ball joint for imparting motion to the rocker arm, a looper attached to the oscillating shaft, and said looper and oscillating shaft capable of adjustment by swinging the clamp bracket relatively to the 75 oscillating arm in order to vary the path of travel of the point of the looper.

2. A needle adjuster for looper machines, where the machine is provided with an oscillating looper arm, an oscillating needle 80 arm, a shaft or spindle journalled in said looper arm, a looper needle carried by the shaft or spindle, connecting means interposed between the shaft and the needle oscillating arm to impress oscillating motion 85 into the shaft or spindle, and an adjustable guide associated with the needle oscillating arm to center the working position of the point of the needle.

3. A looper machine for joining knit fabrics together, said machine having a cylinder for holding the fabrics to be sewed together and having a pair of oscillating arms, a shaft carried by one arm and adapted to oscillate therein, a looper needle fixed to the 90 shaft journalled in one arm, and a stitch needle fixed to the other oscillating arm, a link connected with one oscillating arm and associated with the shaft so as to oscillate the shaft when the arms undergo oscillating 95 motion, and means for varying the action of said link to vary the position of the working point of the looper needle radially of the cylinder which carries the knit fabric.

4. A needle adjuster and guide for sewing machines employed in uniting knit fabrics, where the machine has a looper and a stitch needle, comprising an oscillating looper arm, a clamp bracket pivoted on said oscillating looper arm, a shaft journalled in the clamp bracket, said looper being fixed to said shaft and a socket device to receive and center said stitch needle at the end of its travel to hold it in correct position.

5. In a looper machine for joining knit fabrics together, a looper arm, a swinging bracket mounted on said arm, means for clamping said bracket so as to prevent a swinging action, a shaft rotatably mounted in said bracket, means for clamping the looper to said shaft and means co-acting with said arm for actuating said looper.

6. In a looper machine for joining knit fabrics together, a looper arm, a clamping bracket secured to said arm, a tubular member supported by said clamping bracket, a shaft rotatably mounted in said tubular member, said tubular member being adjustable longitudinally and capable of swinging with said bracket, means for clamping 120

said bracket in any adjusted position, means for clamping the looper to said shaft and means co-acting with said arm for actuating said looper.

5 7. In a looper machine for joining knit fabrics, an arm, a bracket carried by said arm, a tubular member adjustably mounted

in said bracket, a shaft rotatably mounted in said tubular member, a looper secured to said shaft and means co-acting with said 10 arm for causing said looper to be properly actuated.

ADELBERT L. TRAVER.
